UNITED STATES PATENT OFFICE.

NICODEMUS DARGACZEWSKI, OF OMAHA, NEBRASKA.

RAILWAY-CAR BUFFER.

1,099,429.

Specification of Letters Patent. Patented June 9, 1914.

Application filed June 28, 1913. Serial No. 776,453.

To all whom it may concern:

Be it known that I, NICODEMUS DARGACZEWSKI, a citizen of the United States, and a resident of Omaha, in the county of Douglas and State of Nebraska, have invented certain new and useful Improvements in Railway-Car Buffers, of which the following is a specification.

My invention relates to buffering or shock-absorbing devices for use on railway cars, and it is the object thereof to provide a buffer for this purpose having a non-metallic yielding facing for receiving the shock and reducing the noise of the first impact upon the buffer, springs arranged to receive and to yield more or less under the pressure exerted upon the buffer subsequent to the first impact, and means enabling a certain tilting movement of the buffer-head so that its face may engage squarely with a contacting body whose face is not parallel to the end of the car on which the buffer is disposed.

A construction embodying my invention is shown in the accompanying drawings, in which—

Figure 1 is a side view of the buffer and a part of the dead-wood of a car on which it is placed, Fig. 2 is a front view of the same, Fig. 3 is a longitudinal vertical sectional view thereof, and Fig. 4 is a transverse vertical sectional view on the plane of the line $x-x$ of Fig. 3.

There is shown in the drawing a part of the end-framing or dead-wood 1 of a railway car. Ordinarily two of the buffers would be placed on each end of the car, being disposed near the ends of the dead-wood. In the structure shown a rectangular plate 2 is set into the face of the dead-wood and secured thereto by lag-screws 3 which pass through the corner portions of the plate. The circular buffer-plate 4 is connected with the dead-wood plate 2 by bolts 5 which pass slidably through the latter and extend into recesses 6 formed in the dead-wood behind the plate. The plates 2 and 4 are held in a spaced relation to each other by the springs 7 and 8. The heavy spring 7 is arranged centrally to the plates, the smaller springs 8 are disposed one around each of the bolts 5, and the ends of each of the springs fit into shallow recesses formed in the adjacent faces of the plates. The bolts 5 normally hold all of the springs under a certain compression. On

the front face of the plate 4 a circular block or plinth 11 of non-metallic resilient cushioning material, such as rubber, is secured by screws 12 of which the heads are set down into suitable recesses provided therefor in the face of the plinth. On the inner face of the plinth, adjoining the face of the plate 4 are recesses for the heads of the bolts 5.

The operation of the buffer will be apparent from its structure. The first shock or impact of a body striking the buffer will be received by the rubber cushion 11, which will render the blow practically noiseless. If the pressure exerted is greater than the normal or initial compression of the springs 7 and 8, the same will then yield, the inner ends of the bolts 5 passing down into the recesses 6 in the dead-wood. Should the face of the body engaging the buffer not be parallel thereto, the buffer-head may tilt more or less, as required, the springs 8 at one side being compressed more than the others. It will be observed that as the lag-screws 3 are placed at the corners of the plate 2 which extend beyond the periphery of the plate 4, said screws may be inserted or removed and the entire device placed upon or removed from the deadwood without disassembling the parts.

Now, having described my invention, what I claim and desire to secure by Letters Patent is:

1. In a car buffer, the combination with a recessed dead-wood, of a plate fixedly secured thereto, bolts passing slidably through the plate into the recesses in the dead-wood, a second plate connected with the outer ends of said bolts, springs disposed around the bolts between the plates, a spring disposed between the plates and held centrally thereto, and a rubber facing disposed on the side of the outer plate opposite the springs.

2. In a car buffer, a recessed dead-wood, a plate secured thereto, a buffer-plate, bolts connected therewith and extending slidably through the dead-wood plate into the recesses in the dead-wood, and springs disposed between the plates and normally held under compression by the bolts, one of the springs being relatively strong and disposed centrally to the plates, and the other springs being weaker than and arranged symmetrically about the central spring.

3. In a car buffer, a fixed plate, a movable

plate normally disposed parallel to the fixed plate, a heavy spring disposed between the plates centrally thereto, lighter springs disposed between the peripheral portions of the plates, means slidably connected with one of the plates for limiting the separation of the plates and holding the springs normally under a certain compression, and a block of resilient material secured on the

face of the movable plate to receive the first impact of bodies thereon.

In testimony whereof I have hereunto subscribed my name in the presence of two witnesses.

NICODEMUS DARGACZEWSKI.
